UNITED STATES PATENT OFFICE.

GALILEO C. BARR, OF OKLAHOMA, OKLAHOMA.

TAIL-LAMP.

1,203,566.

Specification of Letters Patent.

Patented Nov. 7, 1916.

Application filed February 25, 1915. Serial No. 10,563.

To all whom it may concern:

Be it known that I, GALILEO C. BARR, a citizen of the United States, residing at Oklahoma, in the county of Oklahoma and State of Oklahoma, have invented certain new and useful Improvements in Tail-Lamps, of which the following is a specification.

This invention contemplates an improved lamp for motor vehicles and has as its primary object to provide a lamp structure which will serve in the capacity of an ordinary tail-light and which will also provide a means for properly displaying a license tag or number.

The invention has as a further object to provide a lamp of this character adapted to support a stencil plate having a license number formed therein, in such manner that the said number may be readily observed in the daytime and wherein at night, the said number will be efficiently displayed through being illuminated.

The invention has as a further object in this connection, to provide an arrangement wherein the stencil plate may be readily mounted in position upon the lamp and wherein the webs of the plate coacting with the body portion thereof to define the license number, will be efficiently supported.

A still further object of the invention is to provide an arrangement wherein the translucent plate employed in connection with the tail-light, will be detachably mounted and wherein means will be provided for securely holding the said plate in position.

The invention has as a still further object to provide a construction wherein the illuminating means employed will be readily detachable from the body of the lamp and wherein the body of the lamp will be so formed as to provide an efficient reflector tending to project the rays of the light toward the stencil plate. And the invention has as a still further object to provide a device of this character which may be readily applied to any conventional type of motor vehicle or automobile without the necessity of structural change therein.

Other and incidental objects will appear as the description proceeds and in the drawings wherein I have illustrated the preferred embodiment of the invention, and wherein similar reference characters designate cor-

responding parts throughout the several views.

Figure 1 is a perspective view of my improved tail-light, Fig. 2 is a transverse sectional view particularly illustrating the mounting of the light socket employed as well as the mounting of the stencil plate, Fig. 3 is a horizontal sectional view more particularly showing the mounting of the translucent plate and the stencil plate at the front of the light casing, the said plates, for the sake of clearness, being shown in full lines, and Fig. 4 is a fragmentary sectional view particularly illustrating the mounting of the translucent plate primarily providing the tail-light.

In the preferred embodiment of my invention as illustrated in the drawings, I employ a lamp housing designated as a whole in Fig. 1 by the numeral 10. This housing is preferably substantially triangular and includes a flat bottom wall 11, a top wall 12, and end walls 13 which define a light chamber within the housing, the said housing being open upon one side. As best shown in Fig. 3 of the drawings, the end walls 13 converge toward one side of the housing and merge into a substantially semi-cylindrical wall 14, arranged to provide a reflector for a light as will presently appear. The end walls 13 and the wall 14 adjacent opposite longitudinal edges thereof are provided with flanges 15 which embrace the adjacent margins of the top and bottom walls, to thus hold the several walls 90 of the housing in proper relative position.

The top wall 12, intermediate the ends thereof, is bowed laterally and upwardly to form a substantially semi-conical hood 16 which is closed at its forward end by a substantially flat front wall 17 rising from the top wall 12 adjacent the forward margin thereof, the wall 17 being provided with an opening 18.

Arranged adjacent the inner face of the wall 17 are a plurality of resilient clips 19 which are each preferably formed from a single length of material secured at one extremity, in any suitable manner, to the wall of the hood 16, with the opposite free extremity thereof offset to yieldably engage a translucent closure plate 20, seating against the inner face of the wall 17 and closing the opening 18 therein.

Interposed between the free ends of the

clips 19 and the plate 20, is a metallic clamping plate 21 arranged to seat flatly against the plate 20 and provided with an opening similar to the opening 18 of the wall 17. 5 It will be observed that two of the clips 19 are preferably arranged adjacent the lower edge of the opening 18 while a third clip is arranged adjacent the upper edge of said opening and medially thereof to thus 10 efficiently hold the plate 20 in position, it being observed upon reference to Fig. 2 of the drawings that the lower edge of the said plate and of the clamping plate 21 is supported by the adjacent margin of the top wall 12. By this arrangement, the clamping plate 21 may be readily removed by 15 flexing the free ends of the clips 19 laterally and the closure plate 20 may then be subsequently removed in a similar manner. 20 Thus, should the plate 20 become broken, it may be readily replaced.

Formed on the forward longitudinal edges of the top and bottom walls 11 and 12 and upon the forward edge of one of the 25 side walls 13 or secured thereto in any suitable manner is a channel member 22 adapted to removably receive a translucent closure plate 23, the said closure plate being slidably received within the channel member 30 to close the housing at the forward open end thereof and being insertible within the channel member at one side of the housing.

Seating against the outer face of the plate 23 and removably received within the channel member 22 is a stencil plate 24. The stencil plate 24 is formed with openings defining a license number which may be identified by a letter as illustrated in Fig. 1 of the drawings, also formed in the plate, 40 and the webs of the plate arranged to contact with the body portion thereof to define the said letters or numbers, are supported by bridge pieces or members 25. As best shown in Fig. 1 of the drawings, these 45 bridge pieces are each preferably formed from a piece of wire secured, at one extremity, to the body of the plate and at the other extremity, to the adjacent web, the wires bridging the openings in the plate defining the letters or numbers. In this connection, it is to be observed that the plate 24 while being translucent, is preferably of a solid white color, while the stencil plate 24 is preferably black, so that the license 55 number displayed by the said stencil plate may, in the daytime, be readily observed.

One of the end walls 13 of the housing is extended at the forward open end of the housing to provide a terminal laterally projecting lug or element 26 arranged in a plane substantially parallel with the plane of the member 22 and disposed to detachably support a retaining member 27 preferably connected thereto by a bolt 28. The 65 member 27 is offset adjacent one extremity

thereof as best shown in Fig. 2 of the drawings and is provided with an adjacent terminal transversely extending flange 29 arranged to engage over the adjacent extremities of the plates 23 and 24, the offset portion of the member 27 closing the channel member 22 at the adjacent ends thereof. It will thus be noted that by removing the member 27, the plates 23 and 24 may also be easily removed. 75

Formed in the bottom wall 11 in substantially concentric relation to the semi-cylindrical wall 14 of the housing, is a substantially circular opening 30 and surrounding the said opening in spaced relation thereto, 80 is a laterally extending annular flange 31. The flange 31 is arranged to depend from the outer face of the bottom wall 11, and may be secured thereto in any suitable manner. 85

Arranged within the housing and removably received through the opening 30 is a preferably electric light bulb 32 which is supported by a conventional type of socket 33. Formed on the socket 33 adjacent the outer terminal thereof is an annular collar 34 which is provided with a peripheral screw threaded flange 35 adapted to coact with the flange 31 for detachably connecting the socket and the bulb 32 with the housing. 95

The filament of the light bulb 32 is included in a circuit with a source of electrical energy in any suitable manner and it will be noted that the light rays from the bulb 100 will be projected by the concave face of the wall 14 toward the closure plate 23 to emerge through the openings formed in the said stencil plate 24 and defining the license number. Consequently, the said number 105 may be readily observed at night. It will thus be seen that I provide a very efficient arrangement for displaying the license number while the light rays from the bulb 32 will also be projected by the wall 14 to 110 emerge through the plate 20, which will be colored red to provide a red light signal.

Secured to the end walls 13 of the housing are transversely arranged attaching sleeves 36 which are provided with radially extending terminals 37. Connecting the terminals 37 of each of the sleeves, is a bolt 38, the shank of which is screw threaded to receive a wing nut 39. The sleeves 36 are, as will be well understood, each adapted to 120 receive the shank of a suitable bracket carried by the motor vehicle or automobile for detachably connecting the lamp therewith.

While I have indicated that an electric lamp is preferably employed in connection 125 with my improved tail light, still, it will be seen that the construction which I disclose may be readily adapted for use in connection with an oil lamp or other illuminating means. 130

Having thus described my invention, what I claim and desire to secure by Letters Patent is:—

1. A device of the character described including a housing having a light chamber and provided with an opening, said housing being formed with walls converging away from said opening into a substantially semi-circular wall forming a reflector disposed 10 opposite the said opening, the bottom wall of the housing having an opening formed therein, a flange surrounding the opening in the bottom wall, a socket provided with a flange engaging said first mentioned 15 flange, the socket being adapted to support a lamp projected into the light chamber in front of said reflector, a plate associated with the opening in the housing and adapted to permit the passage of light there- 20 through, and means for holding said plate in position.

2. A device of the character described in-

cluding a housing provided with an opening, a receiving member carried by the housing and provided with an opening, a 25 plate associated with the opening in the housing and mounted in said receiving member, the said plate being adapted to permit the passage of light therethrough, a lug carried by the housing adjacent the opening in 30 said receiving member and projecting laterally from the said member, the said lug being adapted to provide a guide for directing the said plate into the receiving member, and a retaining member carried by said 35 lug and engaging the plate for maintaining the plate in position.

In testimony whereof I affix my signature in presence of two witnesses.
